UNITED STATES PATENT OFFICE.

HARRY F. THURBER, OF NEW HAVEN, CONNECTICUT, ASSIGNOR TO THE GREIST MANUFACTURING COMPANY, OF NEW HAVEN, CONNECTICUT, A CORPORATION OF CONNECTICUT.

DESIGN FOR A LAMP.

Application filed September 15, 1927. Serial No. 23,413. Term of patent 7 years.

To all whom it may concern:

Be it known that I, HARRY F. THURBER, a citizen of the United States and resident of the city of New Haven, in the county of New Haven and State of Connecticut, have invented a new, original, and ornamental Design for a Lamp, of which the following is a specification, reference being had to the accompanying drawings, forming part thereof.

The drawing shows the design in side elevation.

I claim:

The ornamental design for a lamp, substantially as shown.

New Haven, Connecticut, Sept. 13th, 1927.

HARRY F. THURBER.
